(57) **CLAIM**

The ornamental design for an identification clip as shown and described.

DESCRIPTION

FIG. 1 is a front perspective view of the identification clip of a first embodiment;

FIG. 2 is a front view of the identification clip of a first embodiment;

FIG. 3 is a back view of the identification clip of a first embodiment;

FIG. 4 is a left side view of the identification clip of a first embodiment;

FIG. 5 is a right side view of the identification clip of a first embodiment;

FIG. 6 is a top view of the identification clip of a first embodiment;

FIG. 7 is a bottom view of the identification clip of a first embodiment;

FIG. 8 is a front perspective view of the identification clip showing the environment of a first embodiment;

FIG. 9 is a front perspective view of the identification clip of a second embodiment;

FIG. 10 is a front view of the identification clip of a second embodiment;

FIG. 11 is a back view of the identification clip of a second embodiment;

FIG. 12 is a left side view of the identification clip of a second embodiment;

FIG. 13 is a right side view of the identification clip of a second embodiment;

FIG. 14 is a top view of the identification clip of a second embodiment;

FIG. 15 is a bottom view of the identification clip of a second embodiment; and,

FIG. 16 is a front perspective view of the identification clip showing the environment of a second embodiment.

The dash-dash broken lines showing a container in FIGS. 8 and 16 depict environmental subject matter that forms no part of the claimed design, the remaining dash-dash broken

(Continued)

lines illustrate portions of the article that do not form part of the claimed design. The dash-dot-dash broken lines illustrate the boundaries of the claimed design, and form no part of the claimed design.

1 Claim, 16 Drawing Sheets
